UNITED STATES PATENT OFFICE

105,938

DESIGN FOR A TEMPLE MEMBER FOR EYE GLASSES OR SIMILAR ARTICLES

Vern W. Doty, Buffalo, N. Y.

Application May 26, 1936, Serial No. 62,852

Term of patent 7 years

To all whom it may concern:

Be it known that I, Vern W. Doty, a citizen of the United States, residing at 652 Main Street, Buffalo, in the county of Erie and State of New York, have invented a new, original, and ornamental Design for a Temple Member for Eye-glasses or Similar Articles, of which the following is a specification, reference being had to the accompanying drawing, forming a part thereof.

Figure 1 is a side elevation of the temple member for eye glasses embodying my design. Figure 2 is a top plan view thereof. Figure 3 is a cross section taken in the plane of line 3-3, Figure 1, of the same.

The essential feature of my temple member

design consists of the double inwardly-bent pendant portion terminating in a reversely-curved tip, the double-bended portion including an upper section obliquely disposed to its attaching end and a pendant substantially upright section terminating at its end in the comparatively short reversely-curved tip. In cross section, this temple member is of the contour shown in Figure 3 of the drawing.

I claim:

The ornamental design for a temple member for eye glasses or similar articles, substantially as shown and described.

VERN W. DOTY.
